UNITED STATES PATENT OFFICE.

OSCAR W. HAGBERG AND EMIL M. LINDE, OF SAN FRANCISCO, CALIFORNIA.

WINDOW COOLING AND WASHING APPARATUS.

1,402,416.

Specification of Letters Patent.

Patented Jan. 3, 1922.

Application filed May 4, 1921. Serial No. 466,673.

To all whom it may concern:

Be it known that we, OSCAR W. HAGBERG and EMIL M. LINDE, subjects of Sweden and the United States, respectively, residing at 5 the city and county of San Francisco and State of California, have invented a certain new and useful Improvement in Window Cooling and Washing Apparatus, of which the following is a specification.

10 The present invention relates to an attachment for windows particularly those of meat markets, fruit and vegetable stores or any other establishment wherein it is desired to maintain the interior of the store 15 cool, the window clean, and to prevent the accumulation thereon of steam, frost or ice.

By our present apparatus, a thin volume 20 of water is uniformly distributed over the upper edge of a window passing by gravity in a free thin sheet downwardly of the inner window surface affording a free rapid evaporation which will maintain the temperature of the room at a relatively low degree.

Our present invention will by its use 25 enable the display in the window of perishable articles for a considerably longer period than is possible under ordinary non-refrigerating conditions, and due to the 30 novelty of the water sheet flowing on the window will attract the attention of passers-by and serve as an advertising medium.

The invention consists mainly in the provision of means associated with a distributor head for causing the water to flow downwardly of the window in a solid sheet, and 35 at the same time to provide an apparatus which is capable of being readily positioned in co-operative relation with display windows in general, and which is adapted for 40 ready removal at little expense.

With the above mentioned and other objects in view, the invention consists in the novel construction and combination of parts hereinafter described, illustrated in the accompanying drawings, and set forth in the claims hereto appended, it being understood 45 that various changes in the form, proportion, size and minor details of construction within the scope of the claims may be resorted to without departing from the spirit or sacrificing any of the advantages of the invention.

To more fully comprehend the invention, reference is directed to the accompanying 50 drawings, wherein:

Figure 1 is a view in elevation of a win-

dow illustrating our invention associated therewith.

Figure 2 is a vertical sectional view taken on line 2-2 of Figure 1 through the distributor head, distributor screen and distributor pipe.

Figure 3 is a sectional view taken on line 3-3 of Figure 1 disclosing more clearly one of the clamping members.

Figure 4 is a view in broken elevation illustrating a portion of the distributor head, distributor pipe, and distributor screen.

Figure 5 is a sectional view taken on line 5-5 of Figure 1 disclosing the gutter and waste pipe.

Referring more particularly to the several views of the drawings wherein like characters of reference designate corresponding parts, 1 is a sash or frame mounting the glass 2, and extending vertically of one side of the sash or frame 1 is a water feed pipe 3, the supply to which is controlled by a valve 4. The pipe 3 is bent at right angles at its upper end and extends longitudinally of the upper wall of the sash or frame 1, as at 5, to approximately the horizontal center thereof, where it connects with one end of a flexible coupling or hose 6. Extending transversely across the bottom of the sash or frame 1 is a gutter 7 for receiving the water passing down the window 2, and the water drains from the gutter through a waste pipe 8. Disposed transversely of the upper edge of the window 2 is an elongated distributing head 9 substantially triangular in cross section closed at its opposite ends and open for the full area of one face as at 10, the opening being disposed facing the window 2, as in Figures 2 and 3 of the drawings. 95 Within the head 9 is fixed a distributor pipe 11 extending longitudinally thereof and formed within its center with an inlet 12 connected with the feed pipe 3 through the flexible coupling 6. The distributor pipe 11 is perforated as at 13 throughout its length, the perforations being disposed to direct the stream flow issuing therefrom outwardly and downwardly relatively to the opening 10. To obtain a uniform distribution 100 of the water over the entire upper surface of the window 2, to insure a complete covering of the inner surface of the window during the passage of the water downwardly thereover, we interpose between the distributor head 9 and the glass or window 2 a distributor screen 14, preferably of metal,

and the lower edge of the screen is bent or folded rearwardly on itself, as at 14, to provide a portion of double thickness on which the lower edge 15 of the distributor head 9 rests, as in Figures 2 and 3 of the drawings. The longitudinal terminal edges of the screen 14 are reinforced by the reinforcing rods 16 around which the screen is bent, and the rod associated with the lower edge is 5 adapted to lie within the distributor head, and the rod associated with the upper edge is adapted to lie exteriorly and longitudinally of the upper edge 17 of said distributor head for the hereinafter described purpose.

10 It will be apparent that the screen covering on the distributor head which affords a great number of very small outlets between the lower edge 15 of the head 9 and the window 2, insures the water stream leaving 15 the interior of the distributor head in a thin sheet, and it will be understood that by the use of this distributor screen, the surface of the window 2 throughout the entire length of the distributor head is moistened, 20 and, through capillary attraction, the water passes from the folded edge 18 of the screen in a solid sheet instead of in numerous small streams, which may or may not converge after striking the window to pour a 25 solid sheet.

30 To detachably secure the distributor head to the window or glass 2, we mount on the upper member of the sash or frame 1, spring brackets 19, bent as at 20 to overlie the head and each carrying a tension screw 21 which screws are disposed in a plane below the longitudinally raised edge 22 of the head 9. To force the head 9 upwardly 35 against the rod 16, and to in turn force the rod into contact with the shoulder 23, a suitable head engaging clip 24 rests on the edge 22 with one wall or surface extending a short distance over the lower surface of the head 9, which surface is cupped as at 40 45 25 to receive the lower end of the tension screw 21.

It will be observed that the adjustment of the tension screw 21 will direct its force mainly on the lower side of the distributor head 9, and while it will force the edges thereof against the screen 14 to tightly retain the same against the inner surface of the glass or window 2, a lateral pressure is also exerted on the head 9 to force the same 50 upwardly in contact with the shoulder 23.

We claim:

1. The combination of a frame having a glass fitted therein, a distributing head extending transversely of the upper edge 55 thereof, said head having an open side disposed toward the glass, a distributing screen over the open side of the head in

contact with the glass and on which the edges of the open side of the head rest, a perforated distributing pipe disposed longitudinally within the head with its inlet 65 extended rearwardly through said head, a water supply pipe connected therewith, and a clamp carried by the frame and bearing on the head for detachably retaining the 70 screen in tight contact with the glass.

2. The combination of a frame having a glass fitted therein, a distributing head extending transversely of the upper edge thereof, said head having an open side disposed in close proximity to the glass, a fabric positioned between the lower edge of the head opening and the glass and on which said edge bears, a perforated distributing pipe carried by and extending 75 longitudinally within the head with its inlet extended rearwardly through said head, a water supply pipe detachably connected therewith, and a spring clamp carried by the frame and overlying said head and 80 adapted to engage the head to detachably secure the same adjacent to the glass and force the edge of the opening against the fabric to hold the same in contact with the glass, the distributing mechanism affording 85 a water escape at the lower edge of the head, whereby the water is uniformly distributed 90 throughout the length of the head onto the glass.

3. The combination of a frame having a 95 glass fitted therein, an elongated distributing head extending transversely of the upper edge thereof, said head being closed at its opposite ends and substantially triangular in cross section and open for the full area 100 of one face affording a water outlet adjacent to the glass, a perforated distributing pipe disposed longitudinally within the head with its inlet extending rearwardly therefrom and with the perforations disposed toward 105 the lower edge of said opening, a distributing screen positioned in contact with the glass and over said distributing head opening with the edges of said head opening resting thereon, a reinforcing rod carried 110 by the upper and lower edges of said screen, the lower edge of said screen being bent or folded rearwardly to provide a double thickness at the lower outlet edge of said distributing head, a water supply pipe connected with the distributing pipe, and means coacting with the head for detachably retaining the same in position against the screen and the screen against the glass.

In testimony whereof we have signed our 115 names to this specification.

OSCAR W. HAGBERG.
EMIL M. LINDE.
